MULTICARTRIDGE PEN

Emil Hechtle, Oradell, N.J., assignor to Radiant Pen Corp., Kenilworth, N.J.

Filed June 21, 1963, Ser. No. 75,470

Term of patent 14 years

(Cl. D74—17)

FIG. 1 is a perspective view of a multicartridge pen showing my new design.

FIG. 2 is another perspective view thereof rotated 90 degrees to the left.

FIG. 3 is an exploded partially sectioned view illustrating the plunger button employed on each side of the cartridge retaining member as well as the locking holes in the side walls of the barrels.

The side of the pen opposite the clip, not shown, is plain and unornamented.

I claim:

The ornamental design for a multicartridge pen, as shown and described.
